Trifari, Krussman & Fishel, Inc., a corpora-
tion of New York

Application January 2, 1937, Serial No. 66,839

Term of patent 3½ years

To all whom it may concern:

Be it known that I, Alfred Philippe, a citizen
of the United States, residing at New York, in the
county of New York and State of New York,
have invented a new, original, and ornamental
Design for a Brooch or the like, of which the
following is a specification, reference being had
to the accompanying drawing, forming part
thereof, wherein—

Figure 1 is a plan view of a brooch or the
like showing my new design, and

Fig. 2 is a side elevational view, the showing
being in the nature of an outline without a
showing of the jewels in this view.

While I have shown my design embodied in a
brooch, it is contemplated that the same may
be embodied in similar articles of jewelry with-
out departing from the spirit of my invention.

I claim:

The ornamental design for a brooch or the like
substantially as shown and described.

ALFRED PHILIPPE.
